ATTORNEY.

UNITED STATES PATENT OFFICE.

WASHINGTON H. REAMA, OF SPRINGFIELD, OHIO, ASSIGNOR TO THE SPRINGFIELD SILVER PLATE COMPANY, OF SAME PLACE.

CASKET-TRUCK.

SPECIFICATION forming part of Letters Patent No. 614,623, dated November 22, 1898.

Application filed April 14, 1898. Serial No. 677,639. (No model.)

To all whom it may concern:

Be it known that I, WASHINGTON H. REAMA, a citizen of the United States, residing at Springfield, in the county of Clark and State 5 of Ohio, have invented certain new and useful Improvements in Casket Trucks or Pedestals, of which the following is a specification.

My invention relates to improvements in devices for supporting caskets for funeral purposes, and it particularly relates to a wheeled device in the nature of a truck which may be used for supporting a casket and also for transporting the same at funerals, in 10 churches, &c.

15 The object of my invention is to provide a simple device for the purpose which shall form a rigid support for the casket when in use and at the same time be capable of folding in small compass when not in use. I attain this object by the constructions shown 20 in the accompanying drawings, in which—

Figure 1 is a perspective view of a device embodying my invention. Fig. 2 is a sectional view of part of one of the end frames 25 in detail, showing the holding device for retaining the truck or pedestal in its open position. Fig. 3 is a detail view of the same. Fig. 4 is a side elevation, partly broken away, of one of the end bars, showing the retaining 30 devices. Fig. 5 is a detail of the same. Figs. 6 and 7 are views showing a modification. Fig. 8 is a view of the end formed with braces.

Like parts are represented by similar letters of reference in the several views.

35 In constructing my improved truck or support I employ two end frames a a , which may be of any suitable design and consisting, essentially, of side posts a' and cross-bars a^2 . The frames a a are supported on caster-wheels 40 c , which are preferably connected directly to the posts a' , in which the caster-frames are adapted to turn. The frames a are connected together on each side by a series of pivoted levers b and b' in the nature of lazy-tongs.

45 The respective lazy-tong side frames are preferably connected together at the top and bottom by connecting-rods b^2 , which may also serve as pivots for connecting the extremities of the levers b and b' , the said levers being 50 pivoted together at the center by bolts or pins b^3 in a well-known manner. The lower extremity of each of the lazy-tong frames is pivoted by a bolt or other suitable connec-

tion b^4 direct to the end frames a , while the upper extremity of each of these lazy-tongs 55 is connected to the said end frames by a detachable sliding connection hereinafter more fully described, it being understood that one of the series of levers b will be pivoted to each of the end frames and one of the series 60 of levers b' have a sliding connection with each of the same.

The tops of the side posts a' of the frames are each preferably provided with bearing-supports a^3 , preferably of rubber or similar 65 material. The cross-bars a^2 are also provided with similar bearing-supports a^4 , which will lie in a different horizontal plane, the cross-bars being located slightly below the tops of the posts a' . When in position, as shown in 70 Fig. 1, the casket is adapted to rest either on the tops a^3 of the posts a' or between the tops of the same and on the cross-bar a^2 on the respective yielding supports formed thereon, the device being thus adapted for caskets of 75 different sizes, the supports a^4 being preferably arranged in a plane slightly above the cross-rods b^2 of the lazy-tong frames, so that all the weight of the casket is brought directly on the end frames and in larger or 80 heavier caskets directly on the supporting-posts a' , which carry the supporting-wheels.

The levers b and b' , which compose the lazy-tong frames, are preferably formed of rectangular tubing adapted to secure the necessary 85 strength and at the same time render the same very light, and when so constructed the inside wall of the upper extremities of the last levers in the series are each provided with a slotted opening d , and there is mounted within this hollow lever or tube a sliding bar d' . This sliding bar d' is also provided with a slotted opening, as shown at d^2 , (see Fig. 4,) and it projects into the hollow lever sufficiently to embrace the bolt or rod b^3 , which 95 forms the pivoted connection between the levers. The outer end of each of the sliding bars d' is connected by a bolt or screw d^3 to the end frame a , preferably to the end post a' , which is also preferably hollow, the end 100 thereof being closed by a cap a^5 , which projects into the hollow post, the bolt d^3 being adapted to pass through the extended portion of said cap and also furnishes the means for securing the cross-bar a^2 to said post by having the bolt screw-threaded and tapped into 105

the supporting-clip a^6 of said cross-bar. The bolt d^3 is preferably shouldered where it contacts with the outer surface of the post to form a bearing-surface d^4 , which fits in the slot d in the end of the lever. It is also further provided with a head d^5 , which rests against the sliding bar d' , but within the tubular lever. This bolt d^3 is provided on its head with a perforation adapted to receive a spring-bolt e , which is normally pressed into the same by a spring e' , this bolt or pin e being provided with a head e^2 , by means of which it may be withdrawn from the opening in the bolt d^3 . The bolt e and the spring e' are enclosed within a spring-case e^3 , which is secured to the outside of the lazy-tong lever, and it is also preferably provided on opposite sides with depressions e^4 , in which are adapted to fit projections e^5 on the head e^2 , so that by withdrawing the head e^2 and turning it slightly the projections e^5 will be raised out of the depressions e^4 and rest on top of the spring-case, so as to hold the pin or bolt e out of the holes or depressions in the bolts d^3 .

25 It will be understood that the pins e , fitting in the bolts d^3 , furnish the means for securing the ends of the upper extremities of the lazy-tong frames securely to the end frames; but when the said pins are withdrawn these levers may slide on the bearing portions d^4 of the bolt, the bars d' sliding in the hollow portion of said levers. This will permit the lazy-tongs to be folded up, bringing the end frames close together, the locking spring bolts or pins being held out of contact with the sliding lever by turning the heads of said bolts until the projections rest on top of the spring-case. When it is desired to put the truck or pedestal in position for use, the end frames are simply moved outwardly until the sliding levers d' contact with the bolts b^3 , which thus limits the movement of said frames, at which time the spring-bolts will be pressed into the openings to receive the same, and thus lock the parts firmly in their extended position.

50 It will be understood that in mounting the parts the sliding bars d' are placed into the hollow levers through the ends thereof, the ends being afterward closed by a suitable cap b^5 .

55 In Fig. 6 the parts are shown slightly modified to adapt them to the use of a solid lever instead of a hollow lever. In this case the solid lever will be provided with an opening d , the same as before; but this opening would extend entirely through the lever and preferably provided on the inside with a countersunk portion d^6 to receive the head or bolt d^5 .

60 Fig. 7 shows a sectional view through the spring bolt or pin adapted for the same.

65 In Fig. 8 I have shown the end frame provided with braces in the corners to stiffen the same. These braces are frequently made of ornamental form and add to the attractive appearance of the truck or pedestal.

Having thus described my invention, I claim—

1. In a casket-truck, the rigid end frames having the end posts and connecting-bars, wheels pivoted directly to said end frames, 70 lazy-tong side frames connected to said end frames, each series of the levers of said lazy-tong frames being pivoted at one end directly to said end frames and at the other end provided with a detachable sliding connection, 75 substantially as and for the purpose specified.

2. In a casket-truck, the end frames each having the vertical posts and cross-bars connecting the same as described, caster-wheels mounted at the lower ends of each of said posts, and series of extensible lazy-tong frames between the respective end frames each of said frames arranged with a pivoted connection at each of its lower ends and a combined pivoted and sliding connection at each of its 85 upper ends, said connections being adapted to permit an adjustment of said lazy-tongs in vertical parallel planes when the truck is closed, and means, substantially as described, for holding said end frames rigidly in vertical parallel planes when the truck is extended, substantially as and for the purpose specified.

3. The combination with the end frames having the vertical posts, caster-wheels pivoted directly to the same, a cross-bar below the line of the tops of said posts, and yielding supports on said cross-bar, lazy-tong frames connecting said end frames, and cross-bars connecting the respective lazy-tong 100 frames, said lazy-tong cross-bars being arranged below the plane of the supports on said end-frame cross-bars, substantially as specified.

4. The combination with the end frames 105 and the lazy-tong frames connecting the same, of a slotted lever in each of said lazy-tong frames, a bolt connecting said lever to the end frame and passing through said slotted lever, a spring-case on said lever having a pin 110 adapted to engage in said bolt, substantially as and for the purpose specified.

5. The combination with the slotted lever, the end frame, the lever-securing bolt, the spring-case on said lever, and a spring-bolt 115 in said spring-case, and means for holding said spring-bolt in different positions, substantially as specified.

6. The combination with the end frames, the lazy-tong frames, the hollow lazy-tong levers having the slotted inner walls, the inner sliding bar connected to said end frame and having a slotted opening to engage the pivot-bolt of said lever, and means, substantially as described, for connecting said lever to said 125 sliding bar or its bolt, substantially as specified.

In testimony whereof I have hereunto set my hand this 4th day of April, A. D. 1898.

WASHINGTON H. REAMA.
